UNITED STATES PATENT OFFICE.

FRIEDRICH HOTTMANN, OF HEILBRONN, GERMANY.

MEANS FOR PREVENTING THE UNAUTHORIZED ABSTRACTION OF THE CONTENTS OF SAVINGS-BOXES, COLLECTING-BOXES, AND THE LIKE.

No. 891,994.

Specification of Letters Patent.

Patented June 30, 1908.

Application filed June 25, 1907. Serial No. 380,836.

To all whom it may concern:

Be it known that I, FRIEDRICH HOTTMANN, a citizen of the German Empire, residing at Heilbronn, in the Kingdom of Wurtemberg, 5 Empire of Germany, have invented certain new and useful Improvements in Means for Preventing the Unauthorized Abstraction of the Contents of Savings-Boxes, Collecting-Boxes, and the Like, of which the following 10 is a description, reference being had to the accompanying drawing, and to the letters and figures of reference marked thereon.

This invention relates to the safety devices of savings boxes, etc., and, in particular, the 15 invention relates to the so-called household savings boxes, collection boxes (offertories) and the like. Particularly, in families, for the purpose of training children to save, small household savings boxes and banks 20 have been in use, for accumulation and saving of small amounts. Frequently, also, locked savings boxes are loaned out by savings banks, so that the smallest savings can be accumulated at home; the bank keeps the 25 key to permit removal of the contents of the box to be credited to the account of a depositor. Such savings boxes, while provided with an admission channel or passage for coins and with an opening for inserting currency, were insufficiently secured against un- 30 authorized abstraction of the savings. Frequently the outlet of the coin passage has been visible at the admission opening, making it possible to abstract coins and bank 35 notes from the box, by use of suitable implements. Furthermore, it has usually been, when introducing paper money or the like into the prior savings-boxes, to roll the money very tightly, as for this purpose only a circular inlet opening was provided, and this, 40 obviously, must be kept so small that the unauthorized abstraction of the smallest coin through this opening would be impossible. A further drawback was found in the relative 45 position of the inlet opening for coins and the opening for currency. The two openings have usually been situated diametrically to each other, so that by the introduction of very simple implements through the one 50 opening the abstraction of the contents of the box through the other opening was possible.

The recited drawbacks are obviated—or at least reduced to a minimum—by the structures embodying the present invention. 55 The coin admission passage has an inclined

or slanting bottom, so formed that introduced coins fall automatically into the savings box, through a passage or opening not visible from the admission opening. When these two openings are situated directly 60 one above the other, a special angle flap (adjustable in its rotary action) is provided, which also prevents the introduction of a thieving implement through the coin passage. The insertion opening for the currency or paper money is, advantageously, arranged directly under the opening for coins, and is of segmental or other curved shape, in such a manner that the bills need only to be folded, not to be rolled tightly. 70

In the annexed drawings, the invention is illustrated, in conjunction with a home savings box provided with a ball lock.

Figure 1 is a side view of a home savings box, the coin passage with ball lock being 75 shown in vertical section; Fig. 2 is a front view of the savings box; Fig. 3 is a top view, with horizontal section through the coin channel; Fig. 4 is a rear view of the box, showing a partial section across the same; 80 Fig. 5 shows the savings box upside down, in which position the exit of the coin passage is closed; and Fig. 6 shows a coin channel with a flat plate movably arranged above its angular bottom. 85

As seen in Fig. 1, the bottom of the coin inlet channel is angular and consists of an upwardly rising part *e* connected to the slightly curved coin inlet opening *c* of the savings box, and a part *f*, extending from or 90 forming a continuation of the part *e* and sloping downwardly to the rear. Said part *f* is provided, at its rear or lower end, with a groove or channel *g* which serves, in the usual manner, as a container for the balls *k* 95 of the ball-closing device. The coin channel casing is closed at the rear by a vertical wall *h*, the lower part of which, situated over the balls *k*, is bent off obliquely in the same direction as the bottom part *f*, and only leaves 100 free a narrow channel *i* for the passage of the coin, the height of this passage, however, being so measured that the largest pieces of money, for instance, a silver dollar, may still pass through. The balls *k* in the ball 105 groove *g*, have such a position that the inserted coins, when passing the part *i* of the channel pass above the balls without touching the same.

Under the coin insertion opening *c* of the 110

savings boxes is a second segmental or curved slot *d*, for insertion of folded currency, bank notes or the like. The slot *d* is so narrow that the smallest coin can not be abstracted, 5 through the slot, from the box, and a withdrawal of paper money would only be effected by tearing it to pieces.

In the bottom of the box *a* a small door *b* is arranged in the usual manner, which can 10 be secured by a lock, and the contents of the box may be removed after opening this door.

The casing of the box is suitably made from steel and may, if desired, also be hardened in such a manner that the casing of the 15 box can not be damaged by sharp implements, such as metal saws, files or the like.

As apparent from the drawings, coins inserted in the box through the admission opening *c* fall, after their center of gravity 20 has passed beyond the edge at the junction of the bottoms *e*, *f*, upon the bottom of rear part *f* of the coin passage and slide through the outlet opening *i* above the balls *k* automatically into the interior of the box. The 25 outlet opening *i*, in the coin-passage, can not be seen from the admission opening *c* on account of the angular bottom, so that the introduction of an implement for the unauthorized abstraction of money, etc., 30 through the coin passage is rendered extremely difficult. If attempts are made to bring the coins into a position so that they may be more conveniently reached by slanting the box or setting it upside down (see 35 Fig. 5), the usual extremely movable ball lock enters into action at the least slant.

In the arrangement shown in Fig. 6, a plate *m* is pivotally arranged over the angular bottom *e*, *f*, of the coin passage on a pin *l*, 40 which plate in the ordinary position rests in front on the part *e* of the bottom and lies

quite flush with the lower edge of the insertion aperture *c*. As soon as a coin is pushed through the insertion aperture *c* and its center of gravity has passed beyond the pivot *l* 45 of the plate, the plate *m* tilts and its rear part rests on the rear part *f*, of the bottom of the coin passage, the upper part of the plate lying flush with the passage *i* and the coin slips through the passage *i* into the interior of the 50 savings box. The arrangement of the plate *m* has the advantage that the extraction of coins through the coin passage is rendered still more difficult, as any instrument for removing coins must have an extraordinarily 55 complicated form in order to be able to be inserted through these apertures into the interior of the savings box. An extraction of coins is entirely prevented by means of this coin passage. 60

The invention can, obviously, be applied not only to family or other savings boxes, etc., but, if required, also on letter-boxes, automatic vending machines, etc.

What I claim is:

A savings box or the like, comprising a box having a coin passage, the bottom whereof is of angular shape so the outlet opening whereof is not visible from the inlet opening, and said box having a currency-inserting 70 opening arranged underneath the coin passage and of segmental shape and so located that the outlet of the aforesaid coin passage is also not visible through said currency inserting opening. 75

In testimony whereof I affix my signature, in presence of two witnesses.

FRIEDRICH HOTTMANN.
